UNITED STATES PATENT OFFICE

2,219,174

FOLDER

Jasper Derry, Medford, Mass., assignor to Terkelson Machine Company, Boston, Mass., a corporation of Massachusetts

Application April 11, 1939, Serial No. 267,230

6 Claims. (Cl. 270—93)

This invention relates to devices for folding the edge of a paper or similar flexible strip such for example as to the strip edge folding devices employed in machines for spirally winding annular objects, such as pneumatic tires, coils of wire and the like, with a strip of paper.

It is an object of the invention to provide a device of this general character which is adapted to be adjusted for folding one or both edges 10 of strips of different width.

Another object of the invention is the provision of a folding device which is adapted to be adjusted to form folds of different widths at one or both edges of strips of different widths.

15 A further object is to provide a device adapted to be adjusted to form folds at one or both edges of the strip in which the edge of the strip either is turned upward or downward.

A still further object is to provide a device 20 having one or all of the above mentioned features and which also is adapted to form a double fold at the edge of the strip.

The invention will be more clearly understood from the following description in conjunction 25 with the accompanying drawings, in which:

Fig. 1 is a front elevational view of a wrapping machine embodying the invention;

Fig. 2 is an enlarged detail plan view of a portion 30 of the same;

Fig. 3 is an enlarged detail front elevational view of the portion of the machine shown in Fig. 2;

Fig. 4 is a view from the right of Fig. 3;

35 Figs. 5 and 6 are fragmentary detail front elevational views of portions of the structure shown in Fig. 3;

Figs. 7, 8 and 9 are sectional views taken upon the lines 7—7, 8—8 and 9—9 of Fig. 3; and

Fig. 10 is a perspective view of a portion of a 40 strip folded in the device of the invention.

The invention is herein illustrated as applied to a machine of well-known type for wrapping annular objects such, for example, as automobile tires, coils of wire, etc. The frame of said machine comprises a base 15 and a yoke 16 which is pivotally mounted on a shaft 17 journalled in an upright 18 rising from the base 15, said yoke being adjustable about the axis of said shaft, and being secured in adjusted position by a clamp 13

45 carried by a second upright 12. The yoke 16 is provided with guide rollers 19 for an annular shuttle 20 on which is rotatably mounted a roll 14 of paper or other wrapping material. The shuttle 20 is rotated by a friction disk 21 secured to the shaft 17 and driven by a friction pinion 22 on the shaft of an electric motor 23. The tire or other work W to be wrapped is carried by work supporting rollers 24 (only one of which is shown in Fig. 1) which are driven through connections generally indicated at 25, from the mo-

5 tor 23, the arrangement being such that the work W is turned relatively slowly with respect to the speed of rotation of the shuttle 20, so that a strip S of paper or other wrapping material is drawn from the roll 14 and wrapped spirally about the 5 work.

Means is provided for applying a substantially constant tension to the strip S as it is led from the roll 14 to the work W in order to cause the strip to be wrapped tightly and evenly about the 10 work. Such means comprises a brake 26 applied to the roll-holding spindle and mechanism including a lever 27 engaging the periphery of the roll, for automatically proportioning the force 15 with which the brake is applied to the diameter of the roll.

The folding device of the invention comprises a body 30 (Fig. 3) of metal shaped to have the general curvature of a section of the shuttle 20 and having a plurality of integral posts 31 (Figs. 2, 3 and 4) projecting laterally therefrom and engaging the front surface of the shuttle 20 and secured to the latter by bolts 32. A plate 33, providing a supporting surface over which the strip S may move freely, is secured upon the body 20 30 by bolts 34. The plate 33 is provided along its front edge with spaced notches 36 and 37 and on its rear edge with a notch 38 opposite the notch 36.

A cylindrical guide passage 39 is formed in 30 the body 30 near its end which is adjacent the roll 14 and is adapted to receive cylindrical studs 40 which are held securely in any desired adjusted position therein by set screws 41. A plate 42 is fixed upon the outer end of each of the 35 studs 40 and projects upwardly therefrom above the plate 33 and serves as a guide for each of the edges of the strip S. The body 30 also is provided with a cylindrical guide passage 45 adjacent the notches 36 and 38 in the plate 33. Cylindrical studs 43 and 44 extend into the guide passage 45 from the front and rear ends thereof respectively and are held in adjusted position therein by set screws 47. Primary strip folding elements 46 and 48 are secured to the outer ends 45 of the studs 43 and 44 respectively and project upwardly therefrom past the edge of the plate 33. Each of the folding elements 46 and 48 comprises a sheet of metal folded so as to taper longitudinally and is provided with a down turned 50 portion 55 and an upturned portion 56.

The body 30 is provided with a third cylindrical guide passage 60 adjacent the notch 37 adapted to receive one end of a rod 61 which may be held in any desired adjusted position therein 55 by a set screw 62. The outer end of the rod 61 is bent upwardly and curved inwardly to provide a secondary folding element 63 positioned opposite the notch 37. The end of the plate 33 adjacent the folding element 63 is provided with a 60

projection 64 extending from each of its opposite edges. A shaft 66 extends between the projection 64 and carries rolls 67 which project slightly above the surface of the plate 33 and provide a movable surface over which the strip S may be led from the strip folding device to the work W.

A disk 70 having an integral post 71 engaging the front surface of the shuttle 20 between the roll 14 and the plate 33 is secured to the shuttle by a bolt 72. A pair of spaced rods 73 and 74 project forwardly from the disk 70 and provide guides through which the strip S passes as it is fed over the plate 33.

Before using the folding device of the invention the position of each of the studs 40 in the guide 39 is adjusted to bring the guide plates 42 to such positions adjacent the opposite edges of the plate 33 that the space between the plates 42 is just slightly greater than the width of the strip S which is to be folded. The position of each of the studs 43 and 44 also is adjusted in the guide slot 45 to move the folding elements 46 and 48 laterally or in a plane perpendicular to the desired positions adjacent the edge of the plate and with respect to the guide plates 42. If it is desired that either of the primary folding elements form a down turned fold in the edge of the strip S the folding element is adjusted in a plane perpendicular to the plate 33, as indicated by the position of the folding element 46 in Fig. 8, so that the edge of the strip S will engage a downwardly curved portion of the folding element as it passes therethrough and be turned downward. On the other hand, if it is desired to fold the edge of the strip upwardly, the folding element is adjusted in a plane perpendicular to the plate 33, as indicated by the position of the folding element 48 in Fig. 8, so that the edge of the strip will engage an upwardly curved portion of the folding element as it passes therethrough. If either of the folding elements 46 and 48 is adjusted to such a position in a plane perpendicular to the plate 33 that the edge of the strip engages the crotch of the folding element between the down turned portion 55 and the upturned portion 56 thereof, then the folding element will merely serve as a guide for the engaging edge of the strip.

The location of the primary folding elements laterally with respect to the position of the edge of the strip determines the width of the fold and the location of the edges of the strip is determined by the positions of the guide plates 42. When either of the folding elements 46 and 48 is positioned so that the edges of the strip S engage either a down turned or upturned portion thereof, the folding element is said to be in an operative folding position. However, when the folding element is positioned so that the edge of the strip engages the crotch between the upturned and down turned portions thereof, the folding element is said to be in an inoperative folding position and merely serves as a guide for the edge of the strip.

If it is desired to form a double fold at one edge of the strip, the rod 61 is adjusted to a position in the guide passage 60 such that the folding element 63 is spaced laterally inward with respect to the folding element 46. Thus, as the previous folded edge of the strip S engages the element 63 it engages the downwardly

curved portion of the element 63 and is folded inward and downward to form a double fold.

I claim:

1. A strip folding device comprising a body having a supporting surface over which the strip 5 may move freely, means for folding an edge of the strip, said means being constructed to fold the edge of the strip upwardly or downwardly depending upon its position in a plane perpendicular to said surface, and means for mounting said 10 folding means adjacent the edge of said surface for adjustment in a plane perpendicular to said surface.

2. A strip folding device comprising a body having a supporting surface over which the strip 15 may move freely, means for folding an edge of the strip, said means being constructed to fold the edge of the strip upwardly or downwardly depending upon its position in a plane perpendicular to said surface, and means for mounting 20 said folding means adjacent the edge of said surface for adjustment laterally of said surface and in a plane perpendicular to said surface.

3. A strip folding device comprising a body having a supporting surface over which the strip 25 may move freely, separate means for folding the edges of the strip, each of said means being constructed to fold the edge of the strip upwardly or downwardly or not at all depending upon its position in a plane perpendicular to said surface, 30 and means for mounting each of said folding means adjacent the edge of said surface for adjustment in a plane perpendicular to said surface and laterally of said surface into and out of operative folding position. 35

4. A strip folding device comprising a body having a supporting surface over which the strip may move freely, separate primary means for folding the opposite edges of the strip, each of said primary means being constructed to fold the 40 edges of the strip upwardly or downwardly or not at all depending upon its position in a plane perpendicular to said surface, means for mounting each of said primary folding means adjacent the edge of said surface for adjustment in a plane 45 perpendicular to said surface and laterally of said surface into and out of operative folding position, secondary means for forming a second fold in one edge of said strip adapted to be positioned adjacent the edge of said surface at a point 50 spaced longitudinally from said primary folding means, and means for adjusting said secondary folding means laterally of said surface into and out of operative folding position.

5. A strip folding device comprising a body 55 having a supporting surface over which the strip may move freely, a longitudinally tapered folding element having upper and lower curved portions extending laterally inward, and means for mounting said element adjacent an edge of said 60 surface for adjustment in a plane perpendicular to said surface.

6. A strip folding device comprising a body having a supporting surface over which the strip may move freely, a longitudinally tapered folding 65 element having upper and lower curved portions extending laterally inward, and means for mounting said element adjacent an edge of said surface for adjustment in a plane perpendicular to said surface and laterally thereof. 70
